US0D1057672S

(12) **United States Design Patent** (10) Patent No.: **US D1,057,672 S**
(45) Date of Patent: ** Jan. 14, 2025

(54) **REMOTE CONTROL**

- (71) Applicant: **Sleep Number Corporation**, Minneapolis, MN (US)
- (72) Inventors: **Jessica Lynn Dixon**, Ramsey, MN (US); **Stacy Marie Stusynski**, Blaine, MN (US); **Natalie Negus**, Minneapolis, MN (US); **Jeffrey Scott Hartzler**, Minneapolis, MN (US)
- (73) Assignee: **Sleep Number Corporation**, Minneapolis, MN (US)

(**) Term: **15 Years**

(21) Appl. No.: **29/924,373**

(22) Filed: **Jan. 18, 2024**

Related U.S. Application Data

- (62) Division of application No. 29/814,835, filed on Nov. 9, 2021, now Pat. No. Des. 1,018,476.

(57) **CLAIM**

The ornamental design for a remote control, substantially as shown and described.

DESCRIPTION

FIG. 1 is a front perspective view of a second embodiment of a remote control, illustrating our new design; FIG. 2 is a front elevation view thereof; FIG. 3 is a rear elevation view thereof; FIG. 4 is a left side view thereof; FIG. 5 is a right side view thereof; FIG. 6 is a top view thereof; and, FIG. 7 is a bottom view thereof.

The broken lines in the drawings illustrate portions of a remote control that form no part of the claimed design.

1 Claim, 5 Drawing Sheets
